UNITED STATES PATENT OFFICE.

BENNETT GROTTA, OF TAMAQUA, PENNSYLVANIA, ASSIGNOR TO ATLAS POWDER COMPANY, OF WILMINGTON, DELAWARE, A CORPORATION OF DELAWARE.

DEVICE FOR IGNITING FLASH-LIGHT POWDER.

Application filed March 7, 1922. Serial No. 541,878.

To all whom it may concern:

Be it known that I, BENNETT GROTTA, a citizen of the United States, residing at Tamaqua, in the county of Schuylkill and State of Pennsylvania, have invented certain new and useful Improvements in Devices for Igniting Flash-Light Powder, of which the following is a specification.

The object of the present invention is to provide a safe, reliable and convenient device for the ignition of photographic flash light powder. A further object of the invention is to provide a structure of such nature that by its use a single flash may be produced or a plurality of flashes may be produced simultaneously and at different points so that such diffusion and distribution of the light may be secured as will best serve to secure the photograph desired.

Further objects and advantages of the invention will be set forth in the detailed description which follows:

Flash light illumination is rapidly growing in favor, both with the novice and with the professional photographer. Flash light powder consists of a compound or a mixture of compounds capable of burning with great rapidity and producing a quick flash of powerful actinic light, thereby making possible the photographing of objects without the aid of daylight or other illumination. These powders are not only highly inflammable but are also, under certain conditions, highly explosive. The manipulation of such a commodity by a class of people who are utterly unversed in the handling of explosives constitutes a serious obstacle to the universal application of flash light photography.

With the object of reducing to a minimum the danger of manipulating flash light powder and also providing an absolute and convenient means for ignition, I have invented a device which is characterized by the use of an electrically-fired match-head,—an ignition unit which is used extensively in detonators or blasting caps for commercial explosives and which is susceptible of manufacture at a very low cost, the said units consisting of two electrically conducting strips separated by a suitable insulating material and with a match head composition upon one end.

These matches may be either of the low tension or of the so-called high tension type

of construction. A low tension match-head is one having the terminals metallically connected, the connection being surrounded by, and in contact with a combustible mixture. Electrical energy heats the metallic connection, or bridge wire, which, in turn, ignites the combustible match composition. A high tension match-head is one having its terminals bridged by a combustible composition of relatively high electrical resistance. Applied electrical energy produces heat which ignites the match composition. For my purpose, I prefer the low tension type, because it may be ignited by any available source of electrical energy such as power current, magneto machine, hand operated dynamo machines, storage and dry batteries, indiscriminately, whereas in the case of high tension match-heads, the source of electrical energy must be governed by the character of the particular kind of match-head in use.

However, while I have stated a preference, it should be understood that a device involving high-tension match-heads is within the scope of my invention.

In the accompanying drawing illustrative of the application of the principles just described,

Fig. 1 is a plan view of a complete ignitor constructed in accordance with the invention;

Fig. 2 is a front elevation of the structure illustrated in Fig. 1;

Fig. 3 is a detail perspective view illustrating the manner of mounting the ignitors between metallic contact strips;

Fig. 4 illustrates a plug and switch connected by a flexible conductor for closing the circuit from a distant point;

Fig. 5 is a sectional view through one of the match-head ignitors.

Fig. 6 is a diagrammatic view illustrating the manner of connecting a plurality of the ignitors so that they may all be energized simultaneously from a distant point.

Like numerals designate corresponding parts throughout the several figures of the drawing.

Referring now to Fig. 2, *a* designates a strip of cardboard having pieces of metal foil *b* and *c* upon its opposite faces, said pieces of metal foil being insulated from each other by the cardboard. The ends of these pieces of metal foil are united by a small platinum wire *e* which is embedded in

a flash producing material *d*. In use the ignited without exertion and, when a single match-head ignitor of Fig. 2 is placed in the position illustrated in Fig. 3 and between the two metallic contact pieces 1 and 2 (see Fig. 1) at which time the match-head composition *d* projects laterally from between the contact pieces 1 and 2 and overlies the powder-pan 3. The powder pan is supported from a block 5, said block also serving as the support for the strips 1 and 2. The block 5 is mounted upon the upper end of a hollow handle 6 which includes a collar 7 in its length. This collar carries two tubular contact members 8 and 8^a adapted to receive the contact points 8^b and 8^c of a plug 8^d of a usual and well known construction. A circuit may be completed between the contact points 8^b and 8^c through a push button switch 8^e which is connected to the plug 8^b by a flexible cord 8^f in a usual and known way. The contact strip 2 is connected by an insulated bolt 2^a with the sleeve 8. The positive terminal 10^a of a battery 10 makes contact with the inner terminal end of the tubular contact 8^a. A circuit may be completed between the tubular contact members 8 and 8^a either through the medium of the push button switch 8^e, from a distant point, or through the medium of a built-in push button switch 9 carried by the collar 7 and which push button switch includes a bridging piece 9^a adapted to make contact with the inner ends of the tubular contact sleeves or members 8-8^a. The contact strip 1 is grounded upon the block 5 and makes contact with the negative side of the battery at 4. A plug 11 is threaded into the lower end of the hollow handle 6 and through the medium of an interposed spring 12 forces the cells constituting the battery up into the hollow handle and to contacting position. The plug 11 is internally threaded as indicated at 11^a for the reception of the usual camera retaining screw of a camera tripod. By virtue of this construction it is possible to support these devices upon ordinary camera tripods and to utilize as many of them as may be desired to produce a plurality of flashes simultaneously at separated points. The manner of wiring to accomplish the foregoing result is illustrated in Fig. 5 from which it will be seen that by closing the push button switch 8^e shown in Fig. 5 the plurality of igniting devices A will be simultaneously energized. Additionally it is possible to effect the closure of the circuit to an individual igniting device by means of the push button switch 9 and while the device is held in the hand. From the foregoing description it will be seen that the device is capable of efficiently serving the purposes set forth, that it is of such simplicity that it may be manufactured at a small cost and that the elements are so correlated and arranged that the powder is

ignited without exertion and, when a single device is used, with the device at arm's length from the operator. When larger charges are required the circuit may be completed from a distance as set forth. In any case ignition may be effected without distracting the operator's attention from the camera or his subject. The operator is also spared the discomfort of being temporarily blinded as the result of his vision being directed toward the flash. The ignition of the match-head in actual contact with the flash light powder is certain to produce absolute ignition of such powder. The element of compactness secured through the construction described is highly desirable for reporters, tourists, amateurs or others who do photography elsewhere than in a studio. The moment of ignition of the match-head is practically identical with the instant of closing the circuit by the operator. Therefore, the operator can control with precision the time of the flash and can operate his camera or instruct his subjects accordingly. The cost of operating this device is confined to the cost of a single match-head for each flash. A single battery will fire several hundred of these match-heads and, as before stated, these match-heads are susceptible of great economy in manufacture.

I am aware that a resistance wire capable of being heated to incandescence and in contact with the flash light powder has been proposed as a means of ignition, but such a device should not be associated with an igniter which utilizes the flash from a match-head. In contradistinction to such a device, the match-head requires but a very small amount of current, gives instantaneous ignition, and is replaceable at a very small cost.

Having described my invention what I claim is:

1. In combination with an electrically ignitable match-head including a non-conducting shank, strips of conducting material upon the opposite faces of said shank and a match-head composition at the end of said shank, a hollow supporting handle, an open top powder pan supported therefrom, spaced metallic contact strips adapted to receive the shank of the electrically ignitable match-heads between them and to frictionally hold said match-heads in position to project laterally over the top of the powder pan, a battery within said handle and connections between the battery and the said contact strips including a manually operable push button switch mounted upon said handle.
2. A device of the character described, comprising a hollow handle, a powder pan supported therefrom, spaced contact strips at one side of the powder pan and above said handle, a battery within said handle, connections between the battery and the contact strips and a retaining plug at the lower

end of the handle, said plug being threaded for the reception of the usual camera retaining screw of a camera tripod.

3. A structure as recited in claim 2 where-
in the connections between the battery and the contact strips include a pair of circuit controlling elements, one of which is built into and is carried by the handle and the

other of which is controllable from a distant point. 10

In testimony whereof I affix my signature in the presence of two witnesses.

BENNETT GROTTA.
